 Robert McConnell(57) **CLAIM**

The ornamental design for a ratchet binder, as shown and described.

DESCRIPTION

FIG. 1 is a front and side perspective view of a ratchet binder, showing my new design;

FIG. 2 is an enlarged view of the knob portion as seen in FIG. 1, shown with the knob in an alternate position;

FIG. 3 is a side elevation view of FIG. 1;

FIG. 4 is an opposite side elevation view of FIG. 1;

FIG. 5 is a front elevation view of FIG. 1;

FIG. 6 is a cross-section view taken along lines 6-6 of FIG. 5; and,

FIG. 7 is a bottom plan view of FIG. 1.

The broken lines shown in FIGS. 1, 3, 4, 5 and 7 are for the purpose of illustrating the eye, chain and hook attached to the ratchet binder and form no part of the claimed design.
